DESIGN FOR A LAMP

John E. Alcott, Westwood, Mass., assignor to
Sheet Polarizer Company, Inc., Union City,
N. J., a corporation of New Jersey

Application March 15, 1938, Serial No. 75,824

Term of patent 14 years

To all whom it may concern:

Be it known that I, John E. Alcott, a citizen of the United States, residing in Westwood, in the county of Norfolk and State of Massachusetts, have invented a new, original, and ornamental Design for a Lamp, of which the following is a specification, reference being had to the accompanying drawing, forming part thereof,

Figure 1 of the drawing is a view in perspective of a lamp embodying my new design; and

Fig. 2 is a side view in elevation of the lamp shown in Fig. 1.

I claim:

The ornamental design for a lamp, substantially as shown.

JOHN E. ALCOTT.
